2,188,950

SNAP FASTENER

Ernst Jordan, Hamburg, Germany

Application September 10, 1938, Serial No. 229,243
In Germany September 15, 1937

4 Claims. (Cl. 24—211)

The present invention relates to a snap connection for disconnectably connecting relatively thin materials or disconnectably connecting a relatively thin material to a base material.

An object of the present invention resides in the provision of a snap connection of the type specified in which the material to be fastened to another material is provided with openings which are slipped over a button member which member comprises provisions which automatically prevent disconnection of the materials.

A further object of the present invention resides in the provision of a snap connection as specified above whereby the connected materials can be disconnected by manipulation of said button member.

Another object of the present invention resides in the provision of a snap connection of the type specified above in which said button member comprises a plurality of ball members which normally laterally project from the button member, and means permitting pushing of said ball members into the interior of said button member by and when the material having the openings is pushed over said button member.

Other objects of the present invention will be ascertained by a consideration of the following specification and are particularly set forth in the appended claims.

30 In the drawing:

Figure 1 is a longitudinal sectional view of a snap connection according to the present invention in locked condition.

Figure 2 is a longitudinal sectional view of the snap connection illustrated in Figure 1 in open condition, i. e., permitting the attachment and removal of one material to and from another material.

Referring more particularly to the drawing, 1 represents a base material, for example the canvas of a tent to which a fastening element 2 is rigidly connected. Element 2 has a contracted part 3 and diverges upwardly therefrom to a part 4 of larger cross section so that an inverted cone is formed. The upper part 4 of said cone part constitutes a guide for the cap part 5 which may have cylindrical configuration and is pushed over the fastening member 2. A spring member 6 which is situated preferably inside the cap 5 tends to remove said cap from the fastening member 2 and base material 1. Cap member 5 is provided with a plurality of openings 7 into which openings part of individual locking members 8 extends; said locking members are preferably ball shaped and located inside cap 5 and

adjacent to the recess or neck 3 of fastening member 2.

The balls 8 which abut against the cone shaped part of member 2 and part of which balls individually fits into the openings 7 prevent complete removal of cap 5 by the action of spring member 6, i. e., the balls 8 lock push button member 5 in the position illustrated in Figure 1 and vice versa.

9 is the material which is to be fastened to the material 1. Material 9 is provided with a hole 10 which is bordered or reinforced by means of member 10 which is ring-shaped in case of cylindrical configuration of member 5. If member 10 with the material 9 attached thereto is pushed over the cap 5 in the direction of arrows 11, balls 8 and cap 5 are moved downward against the action of spring 6, and balls 8 move inward thereby making way for member 10. As soon as member 10 has passed the narrowest or neck part 3 of member 2, cap 5 snaps upward due to the action of spring 6 and takes balls 8 with it. The latter move upward and outward because of the diverging configuration of part 2 above the neck 3; the device is then in the locking condition illustrated in Figure 1 whereby balls 8 prevent removal of member 10. Fig. 2 shows the snap connection according to the present invention at the moment when member 10 passes the neck 3 and balls 8 are in innermost position.

In order to be able to remove material 9 and member 10, cap 5 must be pressed downward from the position shown in Figure 1 to that shown in Figure 2. Material 9 and member 10 may then be slipped upward and removed from the fastening device and thereby from material 1 or base 1.

The device shown in the drawing and described above is one possible embodiment of the present invention. It is, however, to be understood that it is not desired to be limited to the exact details of design and construction shown and described, for obvious modifications will occur to a person skilled in the art.

What is claimed is:

1. A snap fastener comprising a stationary inner member, an outer member closely fitting over said inner member and being movable relative to said outer member, a resilient means disposed between said members and tending to hold said members in a predetermined position with respect to one another, one of said members having an inclined portion, locking means disposed adjacent to said inclined portion and between said members and projecting from said outer member un-

der the influence of said spring member and inclined portion.

2. A snap fastener comprising a stationary inner member, an outer member movably and closely fitting over said inner member and having an opening, a resilient means disposed in between said members and tending to hold said members in a predetermined position with respect to one another, one of said members having an inclined portion, a locking means disposed adjacent to said inclined portion and between said members and projecting from said outer member through said opening under the influence of said spring member and inclined portion.

15 3. A snap fastener comprising a stationary inner member, an outer member movably and closely fitting over said inner member and having a plurality of openings, a resilient means disposed in between said members and tending to hold said members in a predetermined position with respect to one another, one of said members

having a cone shaped portion, a plurality of locking means disposed adjacent to said cone shaped portion and between said members and individually projecting from said outer member through said openings under the influence of said spring member and inclined portion. 5

4. A snap fastener comprising a stationary rotund center member having a neck portion and a diverging portion above said neck portion, a substantially cylindrical hollow cap member 10 closely and axially slidably fitted over said center member, a plurality of openings in the side of said cap member, a resilient means in-between said members and tending to remove said cap member from said center member, a plurality of 15 rotund locking members disposed in-between said diverging portion and said cap member and extending through said openings and preventing removal of said cap member and being adapted to be pushed from outside into said neck portion. 20
